Specification for Design.

Patented July 25, 1916.

Application filed February 4, 1916. Serial No. 76,219. Term of patent 7 years.

To all whom it may concern:

Be it known that I, HENRY CUSHING HASKINS, a citizen of the United States, residing at Glen Ridge, in the county of Essex and State of New Jersey, have invented a new, original, and ornamental Design for a Handhold for Car-Straps, of which the following is a specification, reference being had to the accompanying drawing, forming part thereof.

The invention is clearly illustrated in the accompanying drawing, in which:—

Figure 1 is a face view; Fig. 2 a top-edge

view; Fig. 3 an end-view; and Fig. 4 a transverse central vertical section of a hand-hold for car straps, showing my new and ornamental design.

I claim:—

The ornamental design for a hand-hold for car straps as shown.

HENRY CUSHING HASKINS.
